UNITED STATES PATENT OFFICE.

ALFRED RE. OF NEW YORK, N. Y.

LOCK.

Application filed December 23, 1920. Serial No. 432,751.

To all whom it may concern:

Be it known that I, ALFRED RE, a citizen of the United States, residing at New York, in the county of New York and State of New York, have invented certain new and useful Improvements in Locks; and I do hereby declare the following to be a full, clear, and exact description of the invention, such as will enable others skilled in the art 10 to which it appertains to make and use the same.

The present invention relates generally to key-controlled locks, and more especially to the type of lock disclosed in my Patent No. 15 1,183,494, granted May 16, 1916.

It is an object of the invention to provide a lock of novel and improved construction and having a novel assemblage and relation of the component elements, whereby the lock 20 is especially useful and efficient.

Another object is the provision of a lock including a key-operated device to be disposed at one side of the door or other object, a latching device to be disposed at the opposite side of the door or object, and a novel operative connection between said devices whereby the latching device is readily controlled by a proper key or keys, and also enabling the lock to be applied to doors or 30 objects of different thicknesses.

A further object is the provision of a simple and inexpensive member for attachment to the inner end of a key cylinder and having means for engagement with a rotary part of a latching device to operate or control the device from said cylinder, and adapted for making the connection when said part and cylinder are spaced different distances apart, such as when used on doors or 40 objects of various thicknesses.

A still further object is the provision of novel means for mounting a latch for swinging movement, to be raised or swung to releasing position either by hand at the corresponding side of the door or object or by the aid of a key at the opposite side of the door or object, including a novel connection between such latch and the key-controlled device whereby the latch can be moved to releasing position even though such device 50 cannot move.

Another object is the provision of novel

means under the control of a key for engaging the latch to prevent movement thereof to releasing position, and so arranged 55 that such means can be locked, when the key is withdrawn, in either position to permit movement of the latch or to prevent movement thereof without the use of such key, in addition to another key used for 60 moving the latch.

With the foregoing and other objects in view, which will be apparent as the description proceeds, the invention resides in the construction and arrangement of parts here- 65 inafter described and claimed, it being understood that changes can be made within the scope of what is claimed without departing from the spirit of the invention.

The invention is illustrated in the accom- 70 panying drawings, wherein:—

Figure 1 is a front view showing the face of the lock and the outer ends of the two cylinders.

Fig. 2 is a rear or inner view of the lock. 75

Fig. 3 is a horizontal section of the lock, portions being shown in full.

Fig. 4 is a rear view showing the latch raised, portions being removed and broken away to show the connection between the 80 latch and its arbor or shaft.

Figs. 5, 6 and 7 are sections on the respective lines 5—5, 6—6 and 7—7 of Fig. 3.

Fig. 8 is a sectional detail on the line 8—8 of Fig. 2 showing the manually-operated 85 means for holding the latch in either position, portions being shown in full.

Fig. 9 is a sectional view on the line 9—9 of Fig. 8.

Fig. 10 is a perspective view of the bush- 90 ing of the means shown in Figs. 8 and 9.

Fig. 11 is a section on the line 11—11 of Fig. 6.

Fig. 12 is a sectional detail on the line 12—12 of Fig. 11. 95

Fig. 13 is a perspective view of the bush- 90 ing of the means shown in Fig. 12.

Fig. 14 is a top view showing a modified form of lock.

Fig. 15 is a face or front view of the modification showing the single key cylinder. 100

Fig. 16 is a detail view of one of the coupling members attachable to the key cylinders.

Fig. 17 is an elevation of such member showing the full-length tongue or extension thereof which can be broken or cut off to accommodate doors or objects of the different thicknesses.

The key device of the lock comprises a block or body 22 to extend within an opening 21 in the door or other object 20, and said block has a marginal flange 23 at its outer end to bear against the outer side of the door 20, and provide a face plate on the exterior. A pair of parallel key cylinders or barrels 24 and 25 are mounted for rotation within the block 22 with their inner ends extending from the block, and the forward or outer ends of said cylinders have flanges 26 seated within the block, to prevent said cylinders from moving inwardly. Each of said cylinders or barrels has a longitudinal key-receiving slot 27 of suitable cross-sectional form, whereby keys 28 and 29 of similar cross section can be slid into said cylinders, and said keys have finger pieces 30 of different outlines or otherwise distinguished from one another, whereby the keys can be used without confusion with such double-key arrangement. A longitudinal series of tumblers 31 is provided for each cylinder and said tumblers are slideable radially within the cylinder at one edge of the key slot 27 to be engaged by the notched or irregular edge of the key, whereby to require a key to correspond with the tumblers, in order to turn the cylinders. The block 22 has bores 32 leading radially from the key cylinders and in which cooperating tumblers 33 are slideable and said tumblers 33 are moved against and into the cylinders by coiled expansion springs 34 within said bores confined between the tumblers 33 and plugs 35 secured in the outer ends of said bores. Such tumbler arrangement is well known, and it will be readily understood that when a cylinder is turned to a position with its tumblers 31 registering with the corresponding tumblers 33, and the key is withdrawn, the springs 34 will urge the tumblers 33 into the holes in the cylinder, thereby pushing the tumblers 31 farther into the cylinder and into the key slot 27. Thus, the tumblers 33 in entering the cylinder will prevent the cylinder from being turned, but when the proper key is inserted, the notched or toothed edge thereof will slide the tumblers 31 away from the slot 27 and push the tumblers 33 out of the cylinder, with the division line of the tumblers coinciding with the surface of the cylinder, so that said cylinder can be turned.

It will be noted, however, by reference to Fig. 7, that two sets of tumblers 33 are provided in the block 22 for the cylinder 25, and are disposed at an angle with one another, whereby the cylinder 25 can be restrained in either corresponding angular po-

sition when the key is withdrawn. Thus, when the cylinder 25 is turned to bring the slot 27 to horizontal position, as seen in Fig. 7, with the tumblers 31 cooperating with the horizontal set of tumblers 33, then the cylinder will be locked in this position when the key is withdrawn, whereas when the cylinder is turned to bring the key slot vertical with the tumblers 31 at the top, said tumblers will cooperate with the vertical 75 tumblers 33 above the cylinder to hold the cylinder in corresponding position when the key is withdrawn. The tumblers 31 of the cylinder 25 thus cooperate with both sets of tumblers 33, under the control of the same 80 key.

In order to fasten the block or member 22 in place, an anchor plate 36 is seated against the inner side of the door or object over the opening 21, and anchor screws 37 are inserted through said plate 36 and screw-threaded into the inner end of the block 22, with the heads of the screws seated in said plate 36, whereby the screws in being tightened will clamp the flange 23 of the 90 block 22 and the plate 36 against the opposite sides of the door. This will prevent the block 22 from being removed from the exterior of the door, and the latching device, which will be described presently, can also 95 be readily applied and removed as a unit, without interference or without disturbing the key device.

The latching device comprises a plate 38 to bear against the plate 36, and secured to the door 20 by means of screws 39 extending through suitable apertures in the plates 38 and 36 and threaded into the door. Said plate 38 has an arcuate boss 40 outstanding therefrom with an opening 41 between the ends thereof, and a plate or disk 42 is secured to said boss by means of screws 43 or the like. An arbor or shaft 44 is mounted to rotate within the plates 36, 38 and 42 centrally thereof, and one end portion of the latch 45 is mounted on said arbor loosely, whereby said arbor can turn and the latch swing independently of one another. Said end portion of the latch extends within the boss 40 through the opening 41, and projects radially. A bushing 46 is preferably secured within the plate 30 in which the arbor 44 is rotatable, and said bushing may fit into the plate 36, as seen in Figs. 3 and 5. The latch 45 is thus mounted for swinging movement, and, as shown, projects beyond the edge of the door 20 to engage a keeper 47 projecting inwardly from the door frame 48. As shown, said keeper has a portion 49 fastened by screws or otherwise to the jamb of the door frame, and has an angular flange 50 overlapping and secured to the inner face of the door frame. Said keeper has a notch 51 into which the latch 45 drops when the door is closed and said latch also has a notch 130

52 to engage the keeper 47, whereby to prevent the latch being withdrawn from the keeper by prying the door away from the frame, such as by means of a "jimmy." A 5 guard plate 53 is also preferably secured to the inner side of the door 20 to bear against the keeper 47 and extends across the gap between the edge of the door and frame, to prevent the insertion of a knife, 10 wire or other implement for the purpose of raising or releasing the latch. The latch 45 has a knob or finger piece 54 extending therefrom to conveniently raise the latch by hand at the inner side of the door, and said 15 latch is arranged to swing downwardly by gravity to latching position, and it will be noted that the swinging movement of the latch is limited by the ends of the boss or rib 40.

20 The latching device has a "night latch" means operable at the inner side of the door to hold the latch in engagement with the keeper, to prevent the latch from being raised by the key, and to also enable the 25 latch to be retained in raised or releasing position if desired. Such means includes a sleeve or bushing 55 screw-threaded or otherwise secured to the plate 42 adjacent to the opening 41 of the boss 40, and a 30 plunger 56 is slideable in said bushing and has a stem 57 projecting from said bushing and on which a knob 58 is secured for manual operation. A coiled expansion spring 59 disposed on the stem 57 within the 35 bushing is confined between the plunger and a shoulder in the bushing, whereby to exert a tension to move the plunger 56 toward the latch 45. In order to retain the plunger in retracted position, the stem 57 and knob 58 40 have a lug 60 to bear against the exposed end of the bushing 55, which has a notched cam portion 61. Thus, when the knob 58 is turned to let the lug 60 move into the portion 61, the spring 59 can move the plunger 45 56 into engagement with the latch, and by turning the knob in the proper direction, the lug 60 in riding along said portion 61 will retract the plunger from the latch and hold said plunger retracted. The latch 45 50 has a socket or recess 62 to receive the plunger 56 when the latch is in lowered position, whereby the latch is held in engagement with the keeper, and can not be released from the exterior of the door, excepting when the plunger 56 is retracted 55 from the inside, thus providing an effective "night latch". The latch 45 has a second socket or recess 63 to receive the plunger 56 when the latch is raised, whereby to hold 60 the latch in such position, when it is desired to keep the latch from engaging the keeper.

The latching device also has a somewhat similar holding means for the latch which, however, is key-controlled to prevent the releasing of the latch without the aid of a

proper key. Such means includes a sleeve or bushing 65 screw-threaded or otherwise secured to the plate 38 adjacent to the opening 41 of the boss 40, and a plunger 66 is slideable in said bushing and has a stem 67 70 projecting from the bushing toward the block 22, and the end of the stem 67 has a diametrical slot 68 for the engagement of a member to turn the plunger 66. A coiled expansion spring 69 surrounding the stem 75 67 within the bushing 65 is confined between the plunger 66 and a shoulder in the bushing, to yieldingly move the plunger against the latch, and pin 70 secured in the stem 67 bears against that end of the bushing opposite to the latch. Such end of the bushing has a notched cam portion 71 in which the pin 70 is movable, and the cam portion will result in the plunger 66 being retracted when the cam 67 is turned in one direction, 80 due to the riding of the pin 70 on the cam away from the latch. When the stem is turned in the opposite direction, the spring 69 can project the plunger into a recess or socket 72 in that side of the latch opposite 90 to the side having the recesses or sockets 62 and 63. The plunger 66 is thus movable into the socket 72 of the latch when the latch is in latching position, in order to hold the latch in such position and prevent raising 95 thereof until the plunger 66 is retracted.

Coming to the operative connection between the key and latching devices, coupling members for that purpose are used between the key cylinders or barrels and the latching device. In the arrangement described and shown, the arbor or shaft 44 is in alinement with the key cylinder 24, while the stem 67 of the plunger 66 is in alinement with the key cylinder 25, and the end of the arbor 100 44 which projects toward the lock 22 also has a diametrical slot 73, resembling the slot 68 of the stem 67. A coupling member is secured to the inner end of each key cylinder for connection with the corresponding 105 part of the latching device. As shown, this member includes a cap 74 fitted on the inner projecting end of the key cylinder and secured thereon by means of a set screw 75 carried by the cap, although other securing 110 means can be used, and to also prevent the outward movement of the cylinder in the block 22. The cap 74 has a flat tongue or extension 76 projecting therefrom along its axis to enter the corresponding slot 68 or 115 73. As shown in Fig. 17, this tongue 76 of the coupling member can be of maximum length before applying the lock to a door, in order that the tongue can be shortened or cut down to the required length, according 120 to the thickness of the door, to take up the space between the key and latching devices. To facilitate the shortening of the tongue, it has transverse nicks or grooves 77 at 125 spaced points along its length, whereby the 130

4

tongue can be broken off or cut off by a file, saw or other suitable implement. In this manner, the coupling members enable the key and latching devices to be used on doors or objects of different thicknesses, and said coupling members can be broken or cut off to the required length, whereby when the caps 76 are secured on the ends of the key cylinders, the tongues will enter the slots 68 and 73 of the plunger 67 and latch arbor 44, respectively. Said coupling members are cut down to required length and the caps 74 thereof secured on the cylinders before the device is applied to the door, and then when the latching device is applied, the arbor 44 and plunger 67 in passing through openings in the plate 36 will move into engagement with the tongues 76 of the respective coupling members, thereby connecting the latch 45 and plunger 66, respectively, with the key cylinders 24 and 25.

In order that the latch 45 will be turned with the arbor 44 and cylinder 24 to releasing position, and to also enable said latch to be raised by itself, a pin 78 is carried by the latch and enters an arcuate groove 79 in the arbor, as seen in Fig. 4, and said arbor has a portion 80 at one end of the groove to contact with the pin 78 and raise the latch when the arbor is turned in one direction. In raising the latch by itself, the pin 78 can readily move into the groove 79 away from the portion 80, without requiring the arbor 44 or the key cylinder 24 to turn, inasmuch as said arbor and cylinder are held in fixed position when the key 28 is withdrawn.

In some cases it may be necessary to limit the turning movement of the key cylinder 20 accurately, and this may be accomplished by having a lug 81 project from the cup 74 of the corresponding cylinder, as shown in connection with the cylinder 24, to strike a stop pin or lug 82 carried by the block or member 22, when the cylinder is turned to a position for the removal of the key.

The operative of the lock will no doubt be obvious to those skilled in the art, from the foregoing description, but briefly described is as follows: The key 29 can be withdrawn in either position of the cylinder 25, with the plunger 66 in or out of engagement with the latch, and said plunger will be prevented from turning because the cylinder 25 is held in either position by the corresponding tumblers 33. Therefore, if the plunger 66 is in engagement with the latch 45, it is first necessary to insert the key 29 and turn the cylinder 25 whereby the stem 67 is turned to retract the plunger 66. The key 28 is then inserted and turned whereby to raise the latch 45, and enable the door to be opened. In closing the door, the latch 45 will drop into the keeper, 65 and the door cannot be opened from the

outside without the aid of the key 28. The key 28 can also be inserted and turned, so as to turn the stem 67 and permit the plunger 66 to enter the socket 72 of the latch, and the key in then being withdrawn, 70 will lock the plunger 66 in such position, thereby requiring both keys to unlock the door, whereas when such key 29 is withdrawn with the plunger in retracted position, only the key 28 is necessary. Whenever 75 the latch is released, it can be raised at the inner side of the door, and the "night latch" plunger 56 can be used whenever desired for holding the latch either in latching or releasing position. 80

With the present construction, the key and latching devices are separate units which are comparatively simple in construction, and they can be readily applied to doors of various thicknesses, and the coupling members provide convenient and efficient means for connecting said devices. 85

In Figs. 14 and 15, a modified form of lock is shown which eliminates the plunger 66, key cylinder 25 and corresponding parts, 90 and the lock is substantially the same otherwise, with the one above described, although the block 22' can be smaller inasmuch as it has only the single key cylinder or barrel 24 therein. 95

Having thus described the invention, what is claimed as new is:

1. A lock comprising a block, a pair of key cylinders mounted for turning movement in said block, key-controlled detent means for preventing the turning movement of said cylinders, an arbor mounted for turning movement connected to one of said cylinders, a latch mounted on said arbor, and a plunger mounted for turning movement to engage and disengage the latch and connected to the other cylinder.

2. A lock comprising a key device having a rotatable key-cylinder, a latching device having a rotatable member with a slot therein, said devices being capable of being secured to the opposite sides of doors or other objects of different thicknesses, and means for operably connecting said cylinder and member for rotation one with the other including a coupling member to be disposed between said cylinder and member having a cap to fit over the inner end of said cylinder and a rigid tongue projecting from said cap, the cap having means for clamping it on said cylinder, and said tongue being of a length to enter said slot. 115

3. A lock comprising a block, a key cylinder mounted for turning movement therein, a latching device comprising a latch and a plunger mounted for turning movement to engage and disengage the latch for holding or releasing it, respectively, said plunger being connected with said cylinder to turn therewith, means for moving a latch, a set 125

of tumblers carried by said cylinder, and two sets of tumblers mounted in said block for cooperation with the key cylinder tumblers in two different positions of said cylinder with said plunger either engaged with or disengaged from the latch.

In testimony whereof I have signed my

name to this specification in the presence of two subscribing witnesses.

ALFRED RE.
